MEDALLION

Isaac Evans, Shaker Heights, Ohio, assignor to
The Master Mechanics Co., Cleveland, Ohio, a
corporation of Ohio

Application May 31, 1950, Serial No. 10,290

Term of patent 14 years

(Cl. D29—2)

To all whom it may concern:

Be it known that I, Isaac Evans, a citizen of the United States, residing at Shaker Heights, in the county of Cuyahoga and State of Ohio, have invented a new, original, and ornamental Design for Medallion, of which the following is a specification, reference being had to the accompanying drawings, forming a part hereof.

Figure 1 is a front view of a medallion, showing my new design.

Figure 2 is an end thereof.

I claim:

The ornamental design for a medallion, substantially as shown.

ISAAC EVANS.
